CLAIM

The ornamental design for a card holder, as shown and described.

DESCRIPTION

FIG. 1 is a first front view of the card holder shown in a closed position. The features of the card holder sequentially transition between the images shown in FIGS. 1-4.

FIG. 2 is a second front view of the card holder shown in a $\frac{1}{4}$ opened position.

FIG. 3 is a third front view of the card holder shown in a $\frac{1}{2}$ opened position.

FIG. 4 is a fourth front view of the card holder shown in a $\frac{3}{4}$ opened position.

FIG. 5 is a fifth front view of the card holder shown in the $\frac{1}{4}$ opened position with a disclaimed gift card. The features of the card holder sequentially transition between the images shown in FIGS. 1 and 5-7.

FIG. 6 is a sixth front view of the card holder shown in the $\frac{1}{2}$ opened position with the disclaimed gift card.

FIG. 7 is a seventh front view of the card holder shown in the $\frac{3}{4}$ opened position with the disclaimed gift card.

FIG. 8 is a right-side view of the card holder with the disclaimed gift card.

FIG. 9 is a left-side view of the card holder with the disclaimed gift card.

FIG. 10 is a top view of the card holder with the disclaimed gift card.

FIG. 11 is a bottom view of the card holder with the disclaimed gift card.

(Continued)

FIG. 12 is a first back view of the card holder of FIG. 1 shown in the closed position. The features of the card holder sequentially transition between the images shown in FIGS. 12-15.

FIG. 13 is a second back view of the card holder of FIG. 12 shown in the 1/4 opened position.

FIG. 14 is a third back view of the card holder of FIG. 12 shown in the 1/2 opened position; and,

FIG. 15 is a fourth back view of the card holder of FIG. 12 shown in the 3/4 opened position.

The broken lines depict portions of the card holder or environment of the card holder that form no part of the claimed design.

1 Claim, 15 Drawing Sheets
